UNITED STATES PATENT OFFICE.

ADOLPH DIETSCHÉ, JR., OF NEW YORK, N. Y., ASSIGNOR TO AMERICAN LITHOGRAPHIC COMPANY, OF NEW YORK, N. Y., A CORPORATION OF NEW YORK.

DISPLAY DEVICE.

Application filed February 23, 1922. Serial No. 538,691.

To all whom it may concern:

Be it known that I, ADOLPH DIETSCHÉ, Junior, a citizen of the United States, and a resident of New York, borough of Queens, 5 in the county of Queens and State of New York, have invented certain new and useful Improvements in Display Devices, of which the following is a specification.

This invention relates to display devices 10 and particularly to that class thereof which is used in connection with containers, one object being to provide a device of the class specified adapted for erection on the upper part of a container in such manner as to be 15 removably but positively and directly engaged therewith.

A further object is to provide means, integral with the wall of the display device, for maintaining that wall in a substantially 20 vertical position or inclined as may be preferred.

Another object is to produce display devices of the type indicated, inexpensive to construct and capable of being closely 25 packed for storage or shipment prior to use.

To these purposes the improvements comprise features hereinafter described in their preferred embodiments, and illustrated in the accompanying drawings, in which:—

30 Figure 1 is a perspective view of a conventional form of common container showing a fragment of a display device, made in the simplest embodiment of the invention, engaged therewith in a substantially vertical position.

35 Fig. 2 is a similar view of a like container showing an adaptation of the display device.

Fig. 3 is a partial plan view of the blank 40 from which the device shown in Fig. 2 is formed.

Fig. 4 is a similar plan view of the blank used in the device as shown in Fig. 1.

45 Fig. 5 is a perspective view looking from the front of a display device having further features of improvement.

Fig. 6 is a rear perspective view of the same.

Fig. 7 is a plan view of a blank from 50 which the display device in Figs. 5 and 6 could be, and that of Fig. 8 is, made.

Fig. 8 is a front perspective view showing the device as applied to a rectangular container.

55 In carrying out the invention any pre-

ferred sheet material may be used that is capable of being bent along creased folding lines and sufficiently stiff to maintain an erect position when applied to a container, the outline or profile of the blank being fancifully ornamental, or plainly rectangular as shown, and dimensioned in accordance with its purpose.

In Figs. 1 and 2, a common type of round container is generically indicated by the numeral 10, the same being provided with a dished end or cover 11 having an upstanding inner wall 12 leading to its narrow annular rim 13.

A simple form of blank, shown in Figs. 70 1 and 4, consists of a body 14 having opposite legs 15 formed by shearing the material from the bottom edge straight up, as at 16, 16, for such distance as may be preferred, commensurate with the container to 75 which the device will be applied, the infacing edges of the legs so formed being spaced apart a distance less than the major transverse dimension of the container.

Said legs terminate at a height uniform 80 from the base line of the body, where the cuts 16 end at short inreaching cross cuts 17, a little greater in length than the thickness of rim 13 of the container, the cuts then continuing downwardly, as at 18, 18, 85 forming recesses 19 suited to engage the rim.

Extending across the blank, between the ends of cuts 18, is creased bending line 20, substantially parallel with the base of the blank, by which horizontal wing 21 is articulated to body 14, said wing being bounded by curved line 22 having its radius at a point below creased line 20, centrally of cuts 18, with which peripheral line 22 connects.

When the device is erected on the container the straight, infacing edges 16 of legs 15 contact with the outer wall of the container, the rim 13 of which enters recesses 19, wing 21 contacts flatwise with the container top and peripheral edge 22 of wing 21 engages upstanding wall 12, bend 20 tending to urge body 14 forwardly, wing 21 downwardly and legs 15, 15 against the 105 container, thus holding body 14 firmly erect on the container.

At the same time inner edges 18 of recesses 19 engage upstanding wall 12 in conjunction with peripheral edge 22 and lo- 110

cate the device against forward movement, while inner edges 16 of legs 15 locate the device against rearward movement, also in conjunction with said edge 22.

5 In the modification of Figs. 2 and 3, the infacing edges of legs 15' are formed with curved profiles 23, respectively, of relatively long radii converging downwardly in such manner that the extremities of the legs are 10 wider than their upper ends, thus holding the body 14' at an angle with the axis of the container, the inclination being obviously rearward.

15 Shearing cut 24 extends from the junction of one of lines 18' and line 22' to the center of wing 21', in alignment with crease 20', and a vertical crease, 25, extends central of said wing, permitting articulation or bending of half the wing upwardly to act 20 as a support, 26, for body 14', as shown in Fig. 2, the remaining half of wing 21' entering the recess in the container cover as before. Cuts 17' and recesses 19' have the 25 same functions as the corresponding parts of Figs. 1 and 4.

Container 30, as shown in Figs. 5 and 6, has raised, outstanding beaded edge 31 and flat head 32, and container 33, in Fig. 8, is indicated as transversely rectangular and 30 having straight sides.

To suit this container a blank, shown in Fig. 7, comprises body portion 35 and legs 36 formed by slitting the material along lines 37 and 37' from the bottom edge to 35 openings 38 and 39, respectively, the former being a partial circle into which line 37 projects, and a transverse shearing cut 40 which extends therefrom to the center of body 35.

40 Crease line 41 continues from sheared cut 40 to the full circular opening 39, and vertical crease 42 extends from the junction of cut 40 and crease 41, centrally of the blank, downwardly to circular opening 43.

45 Thus there is produced a wing, 44, articulated by creased line 41 and having curved peripheral edge 45 conforming to the top of the container.

50 Formed with wing 44 is an L shaped ear element, 46, articulated by creased line 42 and having its outer corner edge bounded by curve 47, struck from the center of opening 43, and extending from said opening 55 straight across to line 37' is sheared cut 48 parallel with the bottom of the blank, forming the upper edge of wing ear 46.

Notch 49 is formed in said edge 48 of ear 46, its purpose later becoming apparent herein.

60 As in the devices previously described, the distance between legs 36 is less than the major transverse dimension of the container, so as to contact upon opposite sides, and the 65 distance between line 48 and articulating crease 41 is such that when the device is ap-

plied, the L shaped ear engages the side of the container, which, in connection with legs 36 constitutes a three point support for the body, which is further secured by wing 44, the beaded rim of the container being received in openings 38, 39 and 43, as clearly shown in Figs. 5 and 6.

70 In the case of a rectangular container, as illustrated in Fig. 8, the blank as last described is used, legs 36 contacting with adjacent sides of the container, and locating the device against rearward movement one of its vertical corners projecting out between said legs while the opposite corner is engaged by the L shaped ear, being held 75 in position by notch 49, the ends of which 80 straddle the corner as shown.

85 From the foregoing disclosure it will be seen that a unitary display device has been shown which can be used with different types of containers for displaying advertisements and the like in an attractive manner, and that the device, when in a "knocked-down" condition, admits of close packing.

90 I claim:

1. A display device adapted for erection on a container and comprising a body of sheet material from one portion of which projects a pair of legs, the infacing edges of said legs being spaced apart a distance less than the major transverse dimension of the container on which the display is adapted for erection, said inner edges being adapted to locate the device against rearward movement, said body having articulated thereto between and on a line substantially normal to the inner edges of said legs a wing member for engagement with the container top, said wing member having an ear articulated thereto adapted to locate the device against forward movement.

100 2. A display device adapted for erection on a container and comprising a body of sheet material from one portion of which projects a pair of legs, the infacing edges of said legs being spaced apart a distance less than the major transverse dimension of the container on which the display is adapted for erection, said inner edges being adapted to locate the device against rearward movement, said body having articulated thereto between and on a line substantially normal to the inner edges of said legs a wing member for engagement with the 105 top of the container and provided with means for locating the device against forward movement, said wing member having an ear articulated thereto on a line in substantial parallelism with the inner edges of said legs, said wing member being adapted 110 for folding substantially normal to said body, and said ear being adapted for folding substantially normal to said wing member whereby an edge of said ear abuts 115 against said body.

3. A display device adapted for erection on the upper portion of a container, comprising a body of sheet material from one portion of which projects a pair of legs, the infacing edges of said legs being spaced apart a distance less than the major transverse dimension of the container on which the display is adapted for erection, said body having articulated thereto between and on a line substantially normal to the inner edges of said legs a wing member, said wing member having an ear articulated thereto on a line in substantial parallelism with the inner edges of said legs, and said ear having an L shaped projection adapted for engagement with a vertical portion of the outer wall of the container when the device is erected.
4. A display device adapted for erection on the upper portion of a container, comprising a body of sheet material from one portion of which projects a pair of legs, the infacing edges of said legs being spaced apart a distance less than the major transverse dimension of the container on which the display is adapted for erection, said body having articulated thereto between and on a line substantially normal to the inner edges of said legs a wing member, said wing member having an ear articulated thereto on a line in substantial parallelism with the inner edges of said legs, said ear having an L shaped projection adapted for engagement with a vertical portion of the outer wall of the container when the device is erected.
5. A display device adapted for erection on the upper portion of a container having a dished end or cover with an upstanding inner wall, comprising a body of sheet material from one portion of which projects a pair of legs, the infacing edges of said legs being spaced apart a distance less than the major transverse dimension of the container on which the display is adapted for erection, said body having articulated thereto between and on a line substantially normal to the inner edges of said legs a wing member having at least a portion of its peripheral edge adapted for engagement with the inner wall of said dished end or cover, said engaging portion having a length greater than one quarter the periphery of said inner wall, said wing member having an ear articulated thereto on a line in substantial parallelism with the inner edges of said legs, and said ear having an L shaped projection adapted for engagement with a vertical portion of the outer wall of the container when the device is erected.

In witness whereof, I hereby affix my signature this 20 day of February, 1922.

ADOLPH DIETSCHE, JR.
